CLAIM

The ornamental design for a rocker arm trunnion tool, as shown and described.

DESCRIPTION

FIG. 1 is a perspective view of the rocker arm trunnion tool; FIG. 2 is a perspective view of the rocker arm trunnion tool in use;

FIG. 3 is top view of the rocker arm trunnion tool of FIG. 1;

FIG. 4 is a front view of the rocker arm trunnion tool of FIG. 1, the back view being mirror symmetrical;

FIG. 5 is a right side view of the rocker arm trunnion tool of FIG. 1;

FIG. 6 is a left side view of the rocker arm trunnion tool of FIG. 1; and,

FIG. 7 is a bottom view of the rocker arm trunnion tool. The broken lines depict portions of the rocker arm trunnion tool that form no part of the claimed design, and are for illustrative purposes only.
